UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,345, dated October 9, 1883.

Application filed July 23, 1883. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

The ground consists of variously-shaped panels bordered by fret-work and ornamented

by various small diagonal ornaments. Disposed irregularly over this ground is an open system of leaf-and-flower work consisting of conspicuous leaf groups—usually three leaves 20 in a group—and smaller star-shaped flower groups—two and three flowers in a group—all arranged on a net-work of stems irregularly traversing the ground.

I claim—

The design for a carpet, substantially as 25 shown and described.

WINTHROP L. JACOBS.
